UNITED STATES PATENT OFFICE.

MILLER WHITE, OF GATESVILLE, TEXAS.

WASHING-MACHINE.

SPECIFICATION forming part of Letters Patent No. 286,245, dated October 9, 1883.

Application filed June 9, 1883. (No model.)

To all whom it may concern:

Be it known that I, MILLER WHITE, of Gatesville, in the county of Coryell and State of Texas, have invented certain new and useful Improvements in Washing-Machines; and I do hereby declare that the following is a full, clear, and exact description of the invention, which will enable others skilled in the art to which it appertains to make and use the same, reference being had to the accompanying drawings, which form a part of this specification, and in which—

Figure 1 is a top view of my improved washing-machine. Fig. 2 is a longitudinal vertical sectional view of the same. Fig. 3 is a cross-sectional view on line x x , Fig. 1, and Fig. 4 is a side view of the rubber attachment removed from the suds-box.

Similar letters of reference indicate corresponding parts in all the figures.

My invention has relation to a washing-machine in which a rubbing-board is suspended in a frame in such a manner as to be vibrated in contact with or contiguous to a concave of rollers journaled in the lower part of such frame, which is removably secured in a tank or suds-box; and it consists in the improved construction and combination of parts of the same, as hereinafter more fully described and claimed.

In the accompanying drawings, A represents a rectangular suds-box, which may be made either of wood or metal, but is preferably made with wooden sides and ends and a zinc bottom, and which is supported upon legs B, of such a length as to raise the machine to a convenient height. The ends of the legs B are inserted into metal sockets C on the sides of the suds-box, so that when it is desired 40 to pack the machine for shipment the legs can be removed by withdrawing their ends from the sockets, thus causing the machine to occupy less space.

D represents a frame of such a width as to fit into the suds-box, and of a length a little less than the inside length of the suds-box. The frame D consists of the side bars, E E, connected by cross-beams F F.

To the middle part of the side bars of the frame D are fastened the lower ends of two

upright posts, G G, the upper ends of which are connected by a cross-bar, H.

In the side bars, E E, of the frame D are journaled the ends of a series of revolving corrugated rollers, I, which are placed side by side and are arranged in the arc of a circle, so as to make the rubbing-surface concave.

J J represent two curved metal strips, which are inserted longitudinally into the side bars, E E, of the frame D, one in each side bar, and serves as a bearing for the ends of the rollers I, the strip J being so placed that its flat side forms the bottom of each of the journal-boxes K, into which the ends of the rollers I are inserted, as will be clearly seen by reference to Fig. 4 of the drawings.

L L represent two swinging bars or arms, the upper ends of which are provided with openings, through which the cross-bar H passes, the swinging bars L L being placed immediately inside of the uprights G G.

N N represent two curved bars or levers, the inner ends of which are provided with holes, through which the cross-bar M, connecting the lower ends of the swinging bars L L, passes, while the outer ends of the levers N N are connected by a cross-bar, O, which serves as a handle in operating the machine.

To the under side of the bars or levers N N, at a little distance from their pivotal point, are secured a series of stationary corrugated rollers, P, to form a rubbing-board.

Fastened to the outside of the lower ends of the uprights G G are vertical cleats Q, of a length corresponding to the depth of the suds-box. These cleats enter vertical grooves R in the middle of the sides of the suds-box, and serve to hold the rubbing attachment firmly in position when placed in the suds-box. An endless apron, S, is fastened around the series of revolving rollers I, and serve to prevent the clothes from being worn or cut by the corrugations on the said rollers, while at the same time the apron is made of a sufficiently yielding material to allow the clothes to enter the corrugations on the rollers I to a certain extent. The roller at each end of the series of revolving rollers I is made plain, as will be seen by reference to the drawings.

The cross-beams F F, which connect the

side pieces of the frame D, have their upper edges beveled to admit of the free passage of the apron S.

T indicates an outlet, through which the water may be drawn off from the suds-box.

From the foregoing description, taken in connection with the accompanying drawings, the construction and operation of my improved washing-machine will readily be understood without requiring extended explanation.

It will be seen that my improved machine is simple in construction, easy to operate, and not liable to get out of order.

15 Having thus described my invention, I claim

and desire to secure by Letters Patent of the United States—

In a reciprocating-rubber washing-machine, the removable concave composed of the frame D, having curved metallic bearing-strips J inserted into the sides E on the under side of and connecting the journal-boxes K and rollers I, constructed and combined as set forth.

In testimony that I claim the foregoing as my own I have hereunto affixed my signature in presence of two witnesses.

MILLER WHITE.
